UNITED STATES PATENT OFFICE.

THOMAS McGLEW, OF SAN FRANCISCO, CALIFORNIA, ASSIGNOR TO THE
McGLEW ORE CONCENTRATOR COMPANY, OF CALIFORNIA.

ORE-CONCENTRATOR.

SPECIFICATION forming part of Letters Patent No. 505,169, dated September 19, 1893.

Application filed April 21, 1892. Serial No. 430,019. (No model.)

To all whom it may concern:

Be it known that I, THOMAS McGLEW, a citizen of the United States, residing at San Francisco, in the county of San Francisco and State 5 of California, have invented certain new and useful Improvements in Ore-Concentrators, of which the following is a specification.

My invention relates especially to concentrators employed for concentrating and saving sulphurets and other valuable particles of metals contained in ores, known as the wet concentration and has for its object the production of a machine, of this character wherein many of the parts heretofore necessary 15 may be dispensed with rendering the machine cheaper in construction, easier to use and more effective in operation, than those heretofore employed.

To this end my invention consists in a shaking table provided with peculiar and novel features or mechanism for imparting the necessary movements for separating the débris or worthless portion of the ore from the heavier or valuable parts, and deliver it in its 25 proper condition at the head of the machine or table.

In the accompanying drawings forming part of the specification, like letters of reference wherever they occur indicate corresponding 30 parts in all of the figures.

Figure 1 is a longitudinal section of my ore concentrator taken through line $y-y$ Fig. 2. Fig. 2 is a plan or top view. Fig. 3 is a section through line $x-x$ Fig. 1 looking to the 35 left. Fig. 4 is a view in detail.

A represents a bed-piece or platform on which the machine is mounted and a head piece or block A^x will support the frame B carrying the driving pulley B^x to which it is 40 rigidly bolted.

To the frame B is hinged the main frame B^2 which supports the shaking-table B^3 and its operating mechanism and permits the latter to be raised or lowered from the lower end 45 on the hinged joint C C that connects the two frames together.

Upon the main or supporting frame B^2 is placed a longitudinal driving cam-shaft D operating in bearings on the cross-beams at 50 the ends of the frame. Two cams D^x D^x on said shaft operate between two vertical lugs

or guide-plates H, H, which are bolted to the under side of the shaking-table B^3 and as the driving shaft is rotated a transverse reciprocating movement is imparted to the table. 55 A universal joint connects the upper end of the shaft D with the pulley driving shaft and a cam-plate F fastened to the under side of the shaking-table B^3 is operated upon by a grooved pulley or wheel f turning around a pin or stud that is secured to the shaft D. A flat spring K is placed across the lower end of the table B^3 the tension of which is controlled by a set screw L having its seat in a cross-bar L^x supported by the brackets or 60 straps M which are bolted to the main-frame B^2 and as the machine is operated the rotary motion of the grooved wheel f through the medium of the cam-plate F together with the reaction of the flat spring K imparts a longitudinal reciprocating movement to the table B^3 which is held down to its seat by means of a strap or bent bar B^4 secured to the under side of the table and reaching across and underneath the shaft D. 70 75

The operation of the grooved wheel f upon the cam-plate will be clearly seen in Fig. 4 in which the full lines indicate in plan view the position of grooved wheel, cam-plate and table B^3 at its extreme longitudinal movement 80 toward the left or against the flat spring K while the dotted lines show the same parts in the position of the table at its extreme longitudinal movement toward the right or the table at rest, the grooved wheel beginning about 85 to operate on the cam-plate.

The tension of the flat spring K is regulated by the set screw L to control the force exerted to impart the return movement to the table. This movement is arrested and the 90 table brought to rest by means of a bumper I of rubber or similar yielding material fixed to a transverse bar I^x which in turn is bolted to straps or brackets I^2 secured to the head of the frame B^2 . 95

A series of friction rollers J connected to the table B^3 form the contact points between the table and the bumper by which means the friction produced between the bumper and the shaking table with its combination of movements is considerably reduced. The table rests upon four friction ball-bearings N, 100

N, N, N, placed at the four corners of the main or supporting frame B² and the balls move in a cup-plate O O^X permanently fixed to the corners of the table and frame as shown.

- 5 In order to provide a means for adjusting the table to a greater or less degree of inclination on its hinged or pivotal point, I have provided the vertical toothed racks P P confined to the outer face of the side beams of 10 the frame B² by guide-plates p and a transverse shaft P^X carrying the pinions P² P² to engage the teeth on the rack and the table will be raised or lowered at will, even during the operating of the machine by means of the 15 crank arm P³ at one end of the transverse shaft.

- In practice the ore with water is fed to the table in the usual way and motion is imparted to the machine by a belt connection 20 with the pulley B^X which causes the longitudinal cam-shaft to revolve and the cam-plate near the head of the shaft to engage the grooved wheel on the pin or stud of the shaft and move the table backward against the flat 25 spring and compress the same until the extreme point of the cam-plate leaves the grooved wheel when the reaction of the flat spring will shoot the table forward, the friction rollers striking against the bumper at 30 the head of the machine and thus percusion of the table is obtained in a longitudinal manner while the cams on the driving shaft will impart a transverse reciprocal motion to the table simultaneously or nearly so. This 35 combination of movements to which the shaking table is subjected produces a spreading out of the ore and water over the whole width of the table, allowing the water and lighter worthless particles as sand and débris to 40 gravitate toward the lower end of the table and to accumulate in a trough R from which it is run off through a pipe connected to the bottom of the trough, while the heavier and valuable particles are carried upward into a 45 trough Q at the upper end of the table, thus separating the gangue from the concentrates which can easily be gathered in said trough to be subjected to further treatment.

The provisions for adjusting the inclination of the shaking table render a ready means to 50 prevent the valuable particles from joining the slime in a downward movement.

Having thus described my invention, what I claim, and desire to secure by Letters Patent, is—

1. The combination in an ore concentrator of a driving pulley, a supporting frame, a vibrating table pivoted thereto, longitudinal cam-shaft having a universal joint connecting with the driving pulley shaft, and a cam-plate fixed to the under side of the table engaging a grooved pulley or wheel on the longitudinal shaft, arranged and operating in the manner, substantially as set forth and specified.

2. A vibrating ore concentrator having friction rollers or wheels at the upper end of the table and a bumper fixed to the frame in line with the friction wheels and engaging the bumper, a resilient spring regulated by a set 70 screw or bolt, and means for vibrating said table, as described.

3. In an ore concentrator the combination with a vibrating table having a transverse reciprocal and a longitudinally reciprocating 75 movement of the friction rollers engaging a bumper fixed to the frame and in line with the rollers, of a resilient spring and a set screw, as and for the purpose set forth.

4. The combination in an ore concentrator 80 of a driving pulley, a supporting frame, a vibrating table pivoted thereto, a longitudinal cam shaft having a universal joint connecting with the driving pulley shaft, cams on said shaft working in guides secured to the under 85 side of said table, and a cam plate fixed to the under side of the said table engaging a grooved pulley or wheel on the longitudinal shaft, arranged and operated as and for the purpose set forth.

In testimony that I claim the foregoing I have hereunto set my hand and seal.

THOMAS McGLEW. [L. S.]
